UNITED STATES PATENT OFFICE.

WILLIAM H. RAMSEY, OF WORCESTER, MASSACHUSETTS.

DESIGN FOR A CORSET.

SPECIFICATION forming part of Design No. 15,215, dated August 5, 1884.

Application filed April 2, 1884. Term of patent 7 years.

To all whom it may concern:

Be it known that I, WILLIAM H. RAMSEY, a citizen of the United States, residing at Worcester, in the county of Worcester and

5 State of Massachusetts, have invented and produced a new and original Design for Corsets, of which the following is a specification, reference being had to the accompanying drawing, forming part thereof, and which represents a side view of a corset, or the right half of a corset to fully illustrate my design.

10 The illustration shows my design as applied to one half of a corset, the other half being of identical ornamentation. Upon the half shown are the sections A, B, C, E, and G, of the usual shape and form, upon which the lines of ornamentation all run parallel with

each other. Sections D and F, also of the usual shape and form, have the lines of ornamentation crossing each other at substantially 20 right angles in diamond pattern.

I claim—

The design for a corset substantially as shown, the same consisting of a plurality of sections in each side or half thereof, having 25 two sets of diagonal ornamenting-lines, crossing each other, interposed between sections having lines running longitudinally of the corset, as set forth.

WILLIAM H. RAMSEY.
